DESIGN FOR A HEAD FOR PORTABLE LAMPS

Lester R. Wellman, Highland Park, Ill., assignor to Will Ross, Inc., Milwaukee, Wis., a corporation

Application September 14, 1936, Serial No. 64,848

Term of patent 3½ years

To all whom it may concern:

Be it known that I, Lester R. Wellman, a citizen of the United States, residing at Highland Park, in the county of Lake and State of Illinois, have invented a new, original, and ornamental Design for a Head for Portable Lamps, of which the following is a specification, reference being had to the accompanying drawing, forming part thereof.

The figure is a side elevational view of a head for portable lamps, showing my new design.

I claim:

The ornamental design for a head for portable lamps, as shown.

LESTER R. WELLMAN.
